(57) **CLAIM**

The ornamental design for a wearable hinged display device, as shown and described.

DESCRIPTION

FIG. 1 is a front perspective view of a wearable hinged display device according to our design in a first configuration;

FIG. 2 is a front elevation view of the wearable hinged display device of FIG. 1;

FIG. 3 is a back elevation view of the wearable hinged display device of FIG. 1;

FIG. 4 is a right elevation view of the wearable hinged display device of FIG. 1;

FIG. 5 is a left elevation view of the wearable hinged display device of FIG. 1;

FIG. 6 is a top elevation view of the wearable hinged display device of FIG. 1;

FIG. 7 is a bottom elevation view of the wearable hinged display device of FIG. 1;

FIG. 8 is another front perspective view of the wearable hinged display device of FIG. 1;

FIG. 9 is a front perspective view of a wearable hinged display device according to our design in a second configuration;

FIG. 10 is a front elevation view of the wearable hinged display device of FIG. 9;

FIG. 11 is a back elevation view of the wearable hinged display device of FIG. 9;

FIG. 12 is a right elevation view of the wearable hinged display device of FIG. 9;

FIG. 13 is a left elevation view of the wearable hinged display device of FIG. 9;

FIG. 14 is a top elevation view of the wearable hinged display device of FIG. 9;

FIG. 15 is a bottom elevation view of the wearable hinged display device of FIG. 9; and,

FIG. 16 is another front perspective view of the wearable hinged display device of FIG. 9.

Broken lines are environmental only and form no part of the claimed design. The dash-dot lines indicate boundaries and form no part of the claimed design.

The lenses shown in the figures are presented with an exemplary thickness and curvature. The thickness and curvature of the lenses is not part of the claimed design.
